UNITED STATES PATENT OFFICE.

JAMES ALLAN WILLIAMS, OF MONTREAL, QUEBEC, CANADA.

ELECTRIC-LIGHT ATTACHMENT.

980,580.

Specification of Letters Patent.

Patented Jan. 3, 1911.

Application filed June 14, 1909. Serial No. 502,112.

To all whom it may concern:

Be it known that I, JAMES ALLAN WILLIAMS, of the city of Montreal, in the Province of Quebec and Dominion of Canada, have invented certain new and useful Improvements in Electric-Light Attachments, of which the following is a full, clear, and exact description.

This invention relates to adjustable brackets or supports for lamps, being especially adapted to carry incandescent electric lamps and the main object of the invention is to provide a support capable of a great variety of adjustments so that when used over desks, drawing tables, and the like, the lamp may be very quickly and easily shifted to any desired position and there supported without the necessity of using any fastening devices.

A further object of the device is to construct a portable bracket or support that can be quickly clamped to a table or desk and that can be extended or contracted without injuring the wires within the bracket.

In the drawings which illustrate this invention:—Figure 1 is an elevation of the bracket or support showing same clamped to a table and showing the various parts in operative relation. Fig. 2 is a plan view of the clamping device. Fig. 3 is a sectional view of the lower joint adjacent the clamping device. Fig. 4 is a sectional view of the telescopic joint between the first and second sections. Fig. 5 is an enlarged sectional view of the joint between the second and third sections. Fig. 6 is an enlarged sectional view of the joint adjacent the lamp socket.

Referring to the drawings, 7 designates the lower clamping plate which is provided on its upper side with a post or standard 8 which is preferably formed integral therewith.

9 designates the upper clamping plate having an apertured boss 10 depending therefrom and through which the post 8 passes.

11 designates the edge of the desk, table, or other support to which the bracket is clamped.

The post 8 is threaded at 12 for a part of its length, and above the plate 9 I provide a nut 13 having a wrench handle 14 pivoted thereto to engage the threaded portion 12 to thus move the clamping plate 9 upwardly or downwardly on the post 8. A small rod 15 is secured to the upper clamping plate and extends downwardly through the lower

clamping plate, said rod being surrounded between the plates by a helical spring 16 adapted to keep said plates apart a suitable distance so as to be ready to be quickly placed in position.

The upper end of the post 8 is plain and adapted to receive the apertured lug 17 of the first joint 18 of the bracket. To hold this joint in position on the post 8, I provide a spring 19, operating in a slot in the post and having a shoulder 20 adapted in its normal position to engage the upper face of the lug 17. The joint 18 is provided with a socket 21 adapted to receive a tube 22 which is securely fastened thereto, the socket 21 and the lug 18 being pivoted together at 23 and being adjustable with relation to each other by means of a thumb nut 24. It will thus be seen that the joint 18 may be revolved upon the post 8, while the socket 21 supporting the telescoping members may be turned angularly upon the pivotal point 23 and clamped in any desired position. The tube 22, which is fastened to the socket 21, is provided at its upper end with interior shoulders 25 and is adapted to receive the tube 26 which telescopes within same, and is provided with the exterior shoulders 27 which act with the shoulders 25 to prevent the tubes from being pulled apart. The tube 26 is provided with a longitudinal slot 28 by means of which the tube may be sprung into smaller circumference and which will hold the sides of said tube in close frictional contact with the interior surface of the tube 22. The tube 26 may thus be telescoped within the tube 22 but will be held frictionally at any desired point without the use of any other means, and may be rotated on its axis within the tube 22 if it becomes desirable to turn the upper part of the bracket through an angle from this joint.

Fixed to the upper end of the tube 26 is a joint 29, the lower half 30 of which is provided with laterally extending bifurcated members 31. The upper half 32 of this joint is provided with a laterally extending tongue 33 which slides between the bifurcated members 31 and is pivoted to same at 34. The member 32 is centrally apertured and provided with interior shoulders 35 adapted to engage the shoulders 36 on the lower end of the tube 37, which is inserted through the aperture of the member 32. The tube 37 may be rotated within the member 32 and can be slid downwardly to tele-

scope into the tube 26 but its movement in the upward direction is limited by means of the shoulders 36. The tube 37 will thus have a movement of rotation within the member 32, and may also be turned angularly with respect to the member 26 by means of the pivoted joint. A suitable thumb nut 38 is adapted to tighten the pivot 34 to hold the upper end of the bracket in any desired position. The top of the tube 37 is provided with a pivoted joint 39 to which the lamp socket 40 may be attached, and by means of this joint the lamp may be turned at any convenient angle with respect to the tube 37. The tubular members 22, 26 and 37 are all adapted to telescope within each other so that the bracket can be contracted practically within the length of one tube or extended to its full length. The interior of the telescopic tubes carries the electric wire or cord 41 which enters at the joint 18 and is connected with the lamp socket 40 at the upper end.

By means of this bracket, several new modifications and adjustments are obtained over any of the brackets heretofore in use, and a lamp may be placed in such a variety

of positions that the device will be found of great convenience to draftsmen, and especially to dentists and physicians who frequently require a lamp capable of all the adjustments herein mentioned. 30

Having thus described my invention, what I claim is:—

A lamp bracket comprising a pair of 35 clamping members having a post mounted thereon, and a plurality of tubular telescopic sections revolvably mounted on said posts, a pivotal joint adjacent the post, means for frictionally engaging the second section 40 within the first, a pivotal joint connecting the extremities of the second and third sections, means for telescoping the third section through the pivotal joint, and a pivotal joint connecting the third section with the lamp 45 socket, said third section being mounted to rotate on its axis.

In witness whereof I have hereunto set my hand in the presence of two witnesses.

J. ALLAN WILLIAMS.
